UNITED STATES PATENT OFFICE.

JACOB H. MACON, JR., OF TAMPA, FLORIDA.

SEWING-MACHINE MOTOR.

SPECIFICATION forming part of Letters Patent No. 757,629, dated April 19, 1904.

Application filed December 24, 1902. Serial No. 136,488. (No model.)

To all whom it may concern:

Be it known that I, JACOB H. MACON, Jr., a citizen of the United States, residing at Tampa, in the county of Hillsboro and State of Florida, have invented a new and useful Sewing-Machine Motor, of which the following is a specification.

This invention relates to motors, and especially to electric motors for sewing-machines; and it has for its object to provide a device of this class which shall be capable of being conveniently applied in operative position to any ordinary sewing-machine, which shall be capable of being easily and conveniently regulated by the operator, and which shall in all respects be simple and efficient.

With these ends in view the invention consists in the improved construction and arrangement of parts, which will be hereinafter fully described, and particularly pointed out in the claim.

In the accompanying drawings, Figure 1 is a top plan view showing my invention applied to the table of an ordinary sewing-machine. Fig. 2 is a vertical sectional view taken on the line 2 2 in Fig. 1. Fig. 3 is a sectional view on a larger scale, taken on the line 3 3 in Fig. 1. Fig. 4 is a top plan view illustrating a slight modification. Fig. 5 is a detail sectional view taken on the line 5 5 in Fig. 2. Fig. 6 is a detail sectional view taken on the line 6 6 in Fig. 4.

Corresponding parts in the several views are indicated by similar numerals of reference.

1 designates the table of an ordinary sewing-machine, of which 2 designates a part of the frame, and 3 the balance-wheel, which is constructed with the usual grooved pulley 4, which is disposed in alinement with the slot 5 in the table, through which a belt or band is usually extended to connect the said pulley 4 with the drive-wheel, ordinarily run by foot-power and which has not been shown in the drawings.

6 designates a table or platform having an extension forming a bracket 7, which is supported upon a corner of the table 1, (or, if preferred, against the under side of the latter, as indicated in Fig. 4 of the drawings,) it being secured in operative position by means of

a pair of clamping-screws 8, which admit of its being very quickly and conveniently applied or detached, as may be required. The table or platform 6 supports an electric motor, which has been conventionally indicated 55 at 9 and which may be of any desired pattern, the shaft 10 of said motor being extended to one side, as shown. Said shaft carries a fixed clutch member consisting of a friction cone-pulley 11 and a loose sliding clutch member consisting of a cylinder 12, having at one end a conical recess 13 to engage the said cone-pulley. The said clutch member 12 has an annular groove 14 in approximate alinement with the pulley 4 of the sewing-machine. 65 It also has an annular groove 15, in which is revolvably seated a band 16, provided with diametrically opposite pins 17, whereby it is loosely connected with the forked end of a lever 18, the prongs of which are provided with slots 19, engaging the said pins. The lever 18, which constitutes the shifting-lever, is mounted pivotally upon the base or table 6 of the motor, as shown at 20, and the said lever may be extended rearwardly under the balance-wheel of 70 the machine, as shown in Figs. 1 and 2 of the drawings, so that the handle thereof shall be conveniently accessible to the operator. In the event of the balance-wheel being too close to the table of the machine to admit of the shifting-lever being conveniently located underneath the same the said shifting-lever may be curved, as shown in Fig. 4, and extended rearwardly at one side of the said balance-wheel. In any case, however, it is essential 75 that the said shifting-lever shall be disposed closely adjacent to the path of the work passing through the sewing-machine and that the handle end of said lever shall be extended to a point in advance of the frame or head of the sewing-machine, so that it shall be disposed within convenient reach of the guiding-hand of the operator. Thus by a slight lateral movement of the hand the said shifting-lever may be moved in either direction 80 to start or to stop the machine.

22 is the belt or band which connects the pulley 4 with the annular groove 14 in the cylindrical clutch member 12.

Suitably connected with the shifting-lever 100

18 is a brake device which comprises a brake-shoe 23, which is adapted to bear against the periphery of the fly-wheel 3. This brake-shoe, as in Fig. 2, may be mounted directly 5 upon the upper side of the shifting-lever, which latter is bent upward, so as to cause it to lie in a plane where the said brake-shoe 23 shall engage the rim of the fly-wheel whenever the shifting-lever is operated to disengage 10 the clutch mechanism for the purpose of stopping the machine. The brake-shoe 23 is preferably wedge-shaped, as shown in Fig. 5, so that it will easily and certainly engage the fly-wheel when the shifting-lever is pushed 15 into the position indicated. It will thus be seen that when the operator actuates the said shifting-lever for the purpose of stopping the machine the brake mechanism is thrown into operation and the stoppage will thus be quickly 20 and effectively performed without the necessity of having recourse to the usual method of manually checking the rotation of the fly-wheel. The shifting-lever will be possessed of some degree of resiliency and will thus 25 hold the brake-shoe in engagement with the fly-wheel with sufficient springiness to avoid a too sudden and injurious action of the brake mechanism.

When the construction illustrated in Fig. 30 4 of the drawings is resorted to, where the fly-wheel 4 is disposed so close to the table as to make it impossible or inconvenient to extend the shifting-lever under the said fly-wheel, the brake-shoe 23 may be suitably connected 35 with the edge of the shifting-lever and be permitted to slide upon the table directly under the fly-wheel, it being, if necessary, disposed to one side of the axial plane. The operation will be identical with that already 40 described, the lateral movement of the shifting-lever serving to engage or disengage the brake-shoe with the periphery of the fly-wheel, according to whether the motor-clutch is thrown out of or into operation.

45 The operation and advantages of this invention will be readily understood from the foregoing description, taken in connection with the drawings hereto annexed. To apply the device in position for operation, it is simply 50 mounted upon or connected with the sewing-machine table by means of the clamping-screws 8, after which the belt or band 22 is adjusted in position upon the pulley 4 and in the annular groove 14 of the cylindrical clutch

member 12. To tighten the belt, it is only 55 necessary to slightly loosen the clamping-screws, and the base 6, with the parts mounted thereon, may be moved in an outward direction from the pulley 4 until the belt is considered to be sufficiently taut, after which the 60 clamping-screws may again be tightened, thus maintaining the device in operative position. To stop the sewing-machine, it is not necessary to stop the electric motor, but only to operate the shifting-lever to disengage the 65 clutch members and operate the brake, the motor continuing in operation, while the work of the sewing-machine is temporarily suspended.

It will be seen that by this device the sewing-machine may be very quickly started or stopped, according to the will of the operator, the electric motor continuing in operation constantly, thereby avoiding the necessity for manipulating the switch or connecting and disconnecting the conductors. If the current gives out or if for any other reason it shall be desirable, the belt may be shifted to the drive-wheel and the machine operated 75 by foot-power.

My improved device is capable of being attached for operation to any sewing-machine of ordinary construction without in the least altering the construction of such machine or preparing it to operate in connection with 85 said device, and the latter when not in use may in a moment's time be detached and stored away.

Having thus described my invention, I claim—

The combination of a supporting-table, a driven machine supported upon said table and including a drive-wheel, a bracket detachably connected with said table, a motor supported upon said bracket, a shifting-lever pivotally 95 connected with the latter, the handle of said lever being extended in proximity to the drive-wheel of the machine supported upon the table, and a brake-shoe connected with said lever and adapted to engage the periphery of 100 the driving-wheel.

In testimony that I claim the foregoing as my own I have hereto affixed my signature in the presence of two witnesses.

JACOB H. MACON, JR.
